Human A. Davenport

UNITED STATES PATENT OFFICE

HERMAN A. DAVENPORT, OF BROCKTON, MASSACHUSETTS, ASSIGNOR TO UNITED SHOE MACHINERY CORPORATION, OF PATERSON, NEW JERSEY, A CORPORATION OF NEW JERSEY

LEVELING MACHINE

Application filed November 8, 1926. Serial No. 147,007.

This invention relates to shoe pressing machines and is disclosed as embodied in an automatic leveling machine of the type shown in United States Letters Patent No. 1,667,761, granted May 1, 1928, on application of E. E. Winkley and H. A. Davenport.

Leveling machines of the type mentioned comprise a reciprocating shoe support or jack and a spring-pressed roll which rolls over a shoe on the jack in response to the movement of the jack. The shank and forepart portions of the sole have been the only ones treated to any substantial extent heretofore in machines of this type, it being impractical to run the roll over the heel-seat, since when it passes the rear end of the heel-seat, it will drop off the shoe, the end of which will be crushed or otherwise damaged as it rolls on again.

The present invention provides novel means whereby the heel end of a shoe as well as other portions may be effectively leveled without danger of damage to the shoe. For the purpose in view the machine herein shown comprises, in addition to a main leveling roll which operates from the toe end of the shoe rearwardly as heretofore in machines of the type illustrated, a pair of rolls supported on a carrier which is mounted independently of the carrier that supports the main roll and so arranged that while one of the pair of rolls passes over the heel-seat and to the rear of the heel end of the shoe in the leveling operation, the other of the pair of rolls remains on the heel-seat and determines positively by its engagement with the shoe the position of that roll which leaves the shoe. The roll which passes beyond the heel end of the shoe is thus maintained at the proper height to return to a position over the heel-seat without damage to the shoe.

The invention also provides various adjustments which enable the forepart and heel-seat leveling rolls to be relatively positioned so as to correspond best to each of the varying types of shoes which are treated in the machine.

These and other features of the invention, including various novel details of construction and combinations of parts, will now be

more particularly described by reference to the accompanying drawings and pointed out in the claims.

In the drawings,

Fig. 1 is a side elevation of the upper front portion of the machine;

Fig. 2 is a perspective view of the leveling tools and adjacent parts; and

Fig. 3 is a fragmentary side elevation, partly in section, of the mechanism shown in Fig. 2.

The main portion of the machine including the frame 10, main roll carrier or arm 12 and shoe support or jack mechanism 14 are substantially as shown in the patent referred to and operate as described therein, the roll carrier 12 being supported on an arm 13 pivoted at 15 on the frame. For purposes of this invention, an additional roll carrier or arm 16 is pivoted at 18 on the machine frame independently of the carrier 12 and has a backwardly extending arm 20 pivoted to a sleeve 22. This sleeve is closed at its upper end by a nut 24 through which slides freely a rod 26 on the upper end of which a nut 28 is threaded. The other end of the rod is pivoted to a knuckle 30 shown as mounted on the arm 13. A stiff spring 32 is confined between the enlarged lower end of the rod 26 and the nut 24, and forces the nut 24 and sleeve 22 toward the nut 28. Thus the limit of downward movement of the front end of the arm 16 is determined by the position of the sleeve 22 as controlled by the nuts 24, 28, and the two nuts together can be adjusted to give the spring any desired compression while maintaining any desired position of the sleeve 22. Obviously the front end of the arm 16 can be raised, compressing the spring by forcing the sleeve downwardly.

The front end of the arm 16 carries a bracket 34 pivoted at 36 and angularly adjustable about its pivot, being held in adjusted position by a clamp at 38. The bracket 34 carries another bracket 40, angularly adjustable in a substantially vertical plane as permitted by slots and bolts 42. Pivots on a substantially vertical axis 44 in the bracket 40 is a third bracket 46 held in adjusted position by a clamp 45. The mount-

ing of the bracket 34 permits the bracket 46 to be adjusted toward and from a main leveling roll 48 on the carrier 12, to accommodate shoes of different lengths, and the other two 5 adjustments provide for turning of the bracket 46 in substantially vertical and horizontal planes, to accommodate shoes on crooked or twisted lasts. It will be understood that the roll 48 operates from the toe 10 end rearwardly on the forepart and shank portions of the shoe as heretofore.

The bracket 46 is shown as an inverted U, and carries a little shaft 50 on which, between the arms of the U, is mounted another U-shaped bracket 52, between the arms of which is a roll 54 on the shaft 50. The bracket 52 carries a second roll 56 just behind the roll 54 with its axis parallel to that of the roll 54. The roll 56 can swing with the bracket 52 20 around the shaft 50, the bracket being confined between a fixed stop 58 and an adjustable stop 60, whereby the swinging movement can be limited or eliminated.

The operation of the machine will be readily understood. As the shoe is thrown under the rolls by the jack, the sole is pressed up 25 against the rolls 54, 56 which pass down over the forepart, shank and heel-seat, the roll 54 passing completely off the end of the heel-seat 30 as the main roll 48 runs down the shank (as shown in Fig. 3). At this time the roll 56 by continued engagement with the shoe bottom supports the bracket 52 and the arm 16 35 positively against the pressure of the spring 32 with the roll 54 substantially in the plane of the heel-seat, i. e., in substantially the same relation to that plane as when operating on the heel-seat, so that as the jack moves back toward the operator the roll 54 will roll back 40 on to the heel-seat without damage to the end of the sole. The rolls 54, 56 may have their surfaces concaved or shaped in any desired way, and the adjustments provided enable the machine to conform to a large range of conditions of work.

The heel-seat is thus rolled down smoothly instead of being pitted by hammer blows, as has been the prior practice.

Having thus described my invention, what 50 I claim as new and desire to secure by Letters Patent of the United States is:

1. In a leveling machine, a tool arranged to pass progressively over and off the heel-seat of a shoe by relative movement of the tool 55 and the shoe, and means positively connected to said tool and arranged to engage the bottom of the shoe to support the tool at approximately the level of the heel-seat after it has passed therefrom, whereby the tool may return to the heel-seat without undue pressure on the edge of said heel-seat.

2. In a leveling machine, a forepart and shank leveling roll, a heel-seat leveling roll, 60 means for causing the heel-seat leveling roll to pass over the heel-seat of a shoe in the ma-

chine and beyond the rear end thereof by relative movement of the shoe and the roll, and positively acting means for engaging the bottom of the shoe to support the heel-seat roll, when not in contact with the heel-seat, 70 substantially in the plane of the heel-seat.

3. In a leveling machine, a roll arranged to be passed over and beyond the rear end of the heel-seat of a shoe in the machine by relative movement of the shoe and the roll, and means comprising a supplemental roll arranged to engage the bottom of the shoe to support said first-named roll positively, when not in contact with the shoe, substantially in the plane of the heel-seat. 75

4. In a leveling machine, an arm carrying a forepart leveling roll, a second arm carrying a heel-seat leveling roll, said second arm being resiliently pressed toward a shoe in the machine, and means for limiting the movement of the arm toward the shoe. 80

5. In a leveling machine, an arm carrying a forepart leveling roll, a second arm carrying a heel-seat leveling roll, said second arm being resiliently pressed toward a shoe in the machine, and means for adjustably limiting the movement of the arm toward the shoe. 85

6. In a leveling machine, a jack, a pivoted arm, a plurality of parallel rolls on said arm arranged to engage the heel-seat of a shoe on the jack, one of said rolls being arranged to pass off the end of the heel-seat and to be supported positively, while off the heel-seat, substantially in the plane of the heel-seat by the continued engagement of another of said rolls 90 with the heel-seat.

7. In a leveling machine, a shoe support, a plurality of leveling tools arranged to operate in locations spaced apart lengthwise of a shoe on said support, different carriers 105 for the different respective tools each mounted independently of the other for movement heightwise of the shoe to press the tool carried thereby upon the bottom of the shoe, the shoe support and said carriers being relatively movable to cause the tools to operate progressively along the bottom of the shoe and to cause one of the tools to pass to the rear of the heel end of the shoe, and means

on the carrier which supports said last-named tool for engaging the bottom of the shoe to prevent any substantial movement of that tool below the plane of the heel-seat when it passes to the rear of the heel end of the shoe. 110

8. In a leveling machine, a shoe support, a plurality of leveling rolls arranged to operate in locations spaced apart lengthwise of a shoe on said support, different carriers for the different respective rolls each mounted independently of the other for movement heightwise of the shoe to press the roll carried thereby upon the bottom of the shoe, the shoe support and said carriers being relatively movable to cause the rolls to operate 115 progressively along the bottom of the shoe.

and to cause one of the rolls to pass to the rear of the heel end of the shoe, and an additional roll mounted on the carrier which supports said last-named roll for engaging the bottom of the shoe to prevent any substantial movement of said last-named roll below the plane of the heel-seat when it leaves the shoe.

9. In a leveling machine, a shoe support, a plurality of leveling rolls arranged to operate in locations spaced apart lengthwise of a shoe on said support, different carriers for the different respective rolls comprising arms mounted for swinging movements relatively 15 to each other heightwise of the shoe to press the rolls carried thereby upon the bottom of the shoe, the shoe support and said carriers being relatively movable to cause the rolls to operate progressively along the bottom of the 20 shoe and to cause one of the rolls to pass to the rear of the heel end of the shoe, and a supplemental roll mounted on the carrier which supports said last-named roll for engaging the bottom of the shoe to prevent any substantial movement of said last-named roll below the plane of the heel-seat when it passes to the rear of the heel end of the shoe.

10. In a leveling machine, a shoe support, a plurality of leveling rolls arranged to operate in locations spaced apart lengthwise of a shoe on said support, different carriers for the different respective rolls each mounted independently of the other for movement heightwise of the shoe to press the roll carried thereby upon the bottom of the shoe, the shoe support and said carriers being relatively movable to cause the rolls to operate progressively along the bottom of the shoe and to cause one of the rolls to pass to the 40 rear of the heel end of the shoe and thereafter to return to a position over the shoe bottom, and an additional roll mounted on the carrier which supports said last-named roll for engaging the bottom of the shoe to determine the 45 relation of said last-named roll to the plane of the heel-seat in its return to a position over the shoe bottom.

11. In a leveling machine, a shoe support, a roll carrier having thereon a leveling roll 50 arranged to operate on the bottom of a shoe on said support from the toe end of the shoe rearwardly, and an additional roll carrier movable heightwise of the shoe relatively to said first-named carrier and having thereon a pair of rolls arranged to operate on portions of the shoe bottom including the heel-seat, the shoe support and said roll carriers being relatively movable to cause the rolls to operate progressively along the bottom of the shoe 55 and to cause one of said pair of rolls to pass to the rear of the heel end of the shoe while the other of the pair of rolls remains in engagement with the bottom of the shoe to determine the relation of that roll which leaves the shoe to the plane of the heel-seat, said pair of rolls being adjustable to vary the angular relation of their axes to the axis of the first-named roll.

12. In a leveling machine, a shoe support, a roll carrier having thereon a leveling roll arranged to operate on the bottom of a shoe on said support from the toe end of the shoe rearwardly, an additional roll carrier mounted for swinging movement heightwise of the shoe relatively to said first-named carrier and having thereon a plurality of rolls spaced apart lengthwise of the shoe and arranged to operate on portions of the shoe at the rear of said first roll, and spring means arranged to act on said additional carrier to press the rolls carried thereby upon the bottom of the shoe, the shoe support and said roll carriers being relatively movable to cause the rolls to operate progressively along the bottom of the shoe and to cause one of the rolls on said additional carrier to pass to the rear of the heel end of the shoe while another of said rolls remains in engagement with the bottom of the shoe to control said additional carrier.

13. In a leveling machine, a shoe support, a roll carrier having thereon a leveling roll arranged to operate on the bottom of a shoe on said support from the toe end of the shoe rearwardly, and an additional roll carrier movable heightwise of the shoe relatively to said first-named carrier and having thereon a pair of rolls arranged to operate on portions of the shoe bottom including the heel-seat, the shoe support and said roll carriers being relatively movable to cause the rolls to operate progressively along the bottom of the shoe and to cause one of said pair of rolls to pass to the rear of the heel end of the shoe while the other of the pair of rolls remains in engagement with the bottom of the shoe to determine the relation of that roll which leaves the shoe to the plane of the heel-seat, said pair of rolls being adjustable to vary the angular relation of their axes to the axis of the first-named roll.

14. In a leveling machine, a shoe support, a roll carrier having thereon a leveling roll arranged to operate on the bottom of a shoe on said support from the toe end of the shoe rearwardly, and an additional roll carrier movable heightwise of the shoe relatively to said first-named carrier and having thereon a pair of rolls arranged to operate on portions of the shoe bottom including the heel-seat, the shoe support and said roll carriers being relatively movable to cause the rolls to operate progressively along the bottom of the shoe and to cause one of said pair of rolls to pass to the rear of the heel end of the shoe while the other of the pair of rolls remains in engagement with the bottom of the shoe to determine the relation of that roll which leaves the shoe to the plane of the heel-seat, said pair of rolls being adjustable lengthwise of the shoe toward and from the first-named roll.

In testimony whereof I have signed my name to this specification.
